(57) **CLAIM**

The ornamental design for a muffler with a heat shield, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front elevation view of a muffler with a heat shield incorporating the new design;

FIG. 2 is a perspective view from a first side of the muffler of FIG. 1;

FIG. 3 is a perspective view from a second side of the muffler of FIG. 1;

FIG. 4 is a perspective view from behind the muffler of FIG. 1;

FIG. 5 is a plan view from below the muffler of FIG. 1;

FIG. 6 is a perspective view from below the muffler of FIG. 1;

FIG. 7 is another perspective view from below the muffler of FIG. 1;

FIG. 8 is another perspective view from below the muffler of FIG. 1;

FIG. 9 is a perspective view from slightly above another muffler with a heat shield incorporating the new design;

FIG. 10 is a perspective view from slightly below the muffler of FIG. 9;

FIG. 11 is a perspective view from in front of and to a first side of the muffler of FIG. 9; and,

FIG. 12 is another perspective view from in front of and to the first side of the muffler of FIG. 9.

The portions of the muffler with a heat shield that are shown ghosted or de-emphasized and are bounded in broken lines do not form part of the claimed design.
